UNITED STATES PATENT OFFICE.

PETER FYFE, OF GLASGOW, SCOTLAND.

GAS-BURNING APPARATUS.

1,074,110.

Specification of Letters Patent. Patented Sept. 30, 1913.

Application filed October 18, 1912. Serial No. 726,464.

To all whom it may concern:

Be it known that I, PETER FYFE, a subject of the King of the United Kingdom of Great Britain and Ireland, and residing at 5 Glasgow, Scotland, have invented a certain new and useful Improvement in Gas-Burning Apparatus, of which the following is a specification.

This invention relates to the consumption 10 of gas or gaseous mixtures in gas burning apparatus in which granular material is employed to divide the gas up into minute streams.

The object of my invention is to construct a gas burning apparatus of this type more particularly adapted for application to domestic fire-grates, ranges, stoves, boilers, heaters and the like which will consume gas at pressures of ordinary supply 20 under the control of a cock or cocks and in which an equalized radiant effect over the entire surface area of the fire is afforded with a minimum of gas consumption and a maximum of heat production. I also aim 25 at producing a gas fire which will approximate closely both in appearance and utility to an ordinary coal fire and which will have a continuous heating surface of substantially the dimensions of the fuel container, 30 fire-grate or the like into which it is fitted.

A further object of my invention is to dispense entirely with an aggregation of separate gas jets or burners arranged within the fuel container, fire-grate or the like.

35 In a gas burning apparatus constructed according to my invention I employ a chamber or chambers or a pan or receptacle of any convenient shape and of any suitable material, into which I conduct a combustible 40 mixture of gas and air. Within the chamber or pan, and at a suitable distance from the bottom thereof, I arrange a sheet of fine wire gauze, coarse linen, buckram, or the like, suitably impregnated so as to be rendered non-inflammable, (or I may use a perforated plate,) which serves the double purpose of acting as a support for the loose 45 non-combustible material to be hereinafter described and also for preventing "firing back" into the pan. Above the gauze I place a layer of loose non-combustible material, such as coarse sand, fine gravel or slag, quartz chips, sifted fire-clay, asbestos particles, or any other suitable loose non- 50 combustible substance; or in order to facilitate the passage of the gaseous mixture I

may advantageously employ small spherical bodies such as iron shot, glass beads and the like. When a combustible mixture is led into the pan it passes through the gauze 55 or the like, percolates through the loose non-combustible material (which offers little or no resistance to the passage of the combustible mixture, thus enabling gas at the ordinary pressure to be employed), and is divided into an infinite number of streams. When ignited the gaseous mixture burns evenly with a hot blue flame over the entire surface of the loose material. I may, if desired, place a thin layer of 60 asbestos wool or other fire-resisting material, in a state of fine division, over the entire area of the loose material in a pan. This material is of such a nature that when highly heated it affords a luminous surface 65 70 75

A gas burning apparatus constructed as above described, when in operation, approximates very closely in appearance to an ordinary coal fire, and can be used for heating water or for cooking purposes generally in the same manner as an ordinary coal fire, while small articles of a combustible nature, such as scraps of paper, cigar and cigarette ends and the like may be consumed 80 upon its surface without any deleterious effect on the efficiency of the fire. A poker or other instrument may also be inserted into the fire and the non-combustible material stirred about without doing any injury. In order to protect the gauze or coarse fabric from possible injury I may place a metal grating or the like upon it. 85 90 95

In the accompanying drawings which illustrate various embodiments of my invention, Figures 1 and 2 show a sectional elevation and plan respectively of a gas burning apparatus embodying the present invention and applied to a modern "interior" grate. Figs. 3 to 9, inclusive, are sectional elevations, to be hereinafter referred to, showing different forms of the invention. 100

Referring first to Figs. 1 and 2, A is a pan or receptacle which is made to fit the space between the fire-brick back and sides B and the cast-iron front C of the fire-grate. D is a ledge or support for the wire frame covered with fine wire gauze, coarse linen buckram or like material E. G is a layer of loose non-combustible material in a state 105 of fine disintegration, which fills the space between the wire gauze and the top of the 110

sisting material in a state of fine division, and granular non-combustible material interposed between said foraminous element and said fire-resisting material and affording a passage for the combustible gaseous mixture.

2. In a gas burning apparatus, the combination of a receptacle having an inlet, and also having an exit at which latter combustion takes place, a Bunsen nozzle at said inlet for supplying a combustible mixture of gas and air to the interior of said receptacle, a foraminous element arranged within said receptacle, said element affording the sole means for the passage of both the gas and the air toward said exit, a layer of fire-re-

sisting material in a state of fine division, granular non-combustible material interposed between said foraminous element and said fire-resisting material and affording a 20 passage for the combustible gaseous mixture, said granular material being located outside of the field of combustion, and means for retaining the said non-combustible and the fire-resisting materials in position. 25

In testimony whereof I have signed my name to this specification in the presence of two subscribing witnesses.

PETER FYFE.
